(57) **CLAIM**

The ornamental design for a hunting stand platform, as shown and described.

DESCRIPTION

FIG. 1 is a top view of a hunting stand platform showing my new design;

FIG. 2 is a bottom view of the hunting stand platform;
FIG. 3 is a right side view of the hunting stand platform, a left side view being a mirror image thereof;

FIG. 4 is a front view of the hunting stand platform;
FIG. 5 is a rear view of the hunting stand platform; and,
FIG. 6 is a rear, top isometric view of the hunting stand platform.

The broken lines represent features of the hunting stand platform which form no part of the claimed design.
